UNITED STATES PATENT OFFICE.

OSCAR H. CARLSON, OF NEW YORK, N. Y., ASSIGNOR TO ESTEY PIANO COMPANY, OF NEW YORK, N. Y., A CORPORATION OF NEW YORK.

PLAYER PIANO.

Application filed December 20, 1919. Serial No. 346,246.

To all whom it may concern:

Be it known that I, OSCAR H. CARLSON, a citizen of the United States, residing at 7 Manhattan Ave., New York, in the county 5 of New York and State of New York, have invented certain new and useful Improvements in Player Pianos, of which the following is a full, clear, and exact description, such as will enable others skilled in 10 the art to which it appertains to make and use the same.

This invention relates to player-pianos, and with regard to its more specific features to devices for operating the treadle door 15 and extending the treadles of the piano.

An object of the invention is to provide a player-piano with improved means for moving the treadles thereof to operative or inoperative positions, and for moving correspondingly a closure for the treadle opening. 20

Another object is to provide a piano having a panel with a treadle opening therein and a closure for the opening, with a simple 25 and reliable closure operating means and treadle operating means which will permit the removal of the panel without disturbing said treadle operating means.

Another object of the invention is to provide a single operating means capable of 30 easily and smoothly operating the treadle door and extending the treadles of a player-piano and which will be simple in construction, economical to manufacture and simple 35 and positive in operation.

Another object is to provide an improved door and treadle operating means for a player-piano adapted to open the treadle door and lower the treadles in sequence to 40 operative positions and to cushion the movement of said parts.

Other objects will be in part obvious and in part pointed out hereinafter.

In the accompanying drawings forming 45 a part of this specification, wherein is illustrated one embodiment of the invention,

Figure 1 is an elevation of the lower part of a player-piano embodying this invention;

Fig. 2 is a slightly enlarged fragmentary 50 rear elevation of the front board removed from the piano frame and showing the door in open position;

Fig. 3 is a fragmentary front elevation with the panel removed showing the operat-

ing mechanism and showing the treadle in 55 folded position and the door (dotted lines) in open position;

Fig. 4 is a side elevation of the door and treadle operating mechanism, the treadles being in folded position and the operating 60 mechanism in position as shown in Fig. 3.

Fig. 5 is a similar view with the treadles in extended position; and

Fig. 6 is an enlarged rear elevation of a detail showing a connection in the treadle 65 operating mechanism which affords lost motion to said mechanism.

Referring more particularly to the illustrated embodiment of the invention, the numeral 1 indicates a player-piano of the upright type having a keyboard 2, a front panel 3 below the keyboard, and pedals 4. The keyboard and pedals are employed when 70 the piano is to be operated manually as is common in instruments of this type. 75

The panel 3 is preferably constructed so as to be readily removable from the piano case, and has at the lower edge thereof an opening which is arranged to be closed by a door or closure 5. This door is slidably 80 mounted, as by straps or hangers 6, on a rod 7 which is mounted longitudinally by means of suitable supports on the inner face of panel 3, as clearly shown in Fig. 2. Movement limiting stops 8 may be employed to 85 limit the movement of the door in both extreme positions and these may be conveniently supplied with cushioning pads, as of felt, to silence the impact of the door in opening or closing movements. Also mounted 90 on the back of the panel and arranged for sliding engagement with door 5 are cushioning strips 9 of any suitable material so that the operation of the door is rendered smooth and noiseless. 95

The sliding movement to open or to closed position is imparted to the door 5 by suitable operating means, part of which is mounted on the back of panel 3. This part of the door operating mechanism includes 100 a slotted member 10 pivotally mounted on the plate 11 on panel 3 and having rigidly secured thereto and extending at an angle therefrom a crank 12 which is connected by the link 13 to a swinging pivoted arm 14, 105 the latter being connected by a link 15 with the door. The member 10 is adapted to be connected through an open-ended slot 16

therein with other parts of the operating mechanism to be hereinafter more fully described.

Mounted beneath the keyboard of the piano in suitable bearings 17 which are secured to portions of the framework, is a transversely disposed operating shaft 18 extending across the upper edge of the panel 3 and having at its outer extremity an angularly disposed operating handle 19 and at its inner extremity rigidly secured thereto a crank 20. Securely mounted at the free end of this crank is a pin 21 which is adapted to engage with slot 16 of pivoted member 10 when the panel is in assembled position on the front of the piano.

A bellows 22 having a stationary member 23 and a movable member 24 may be employed to supply motive power when the instrument is used as a player-piano. Treadles 25, each pivotally mounted at one end to a support or footboard 26, are operatively connected at their free ends as by links 27 with the movable member 24 of the bellows so that the latter may be operated manually to perform its function. Footboard 26 may have one or more cushioned feet 28 for engaging the floor and supporting the treadles in operative or extended position. Cushions 29 may be employed to engage the treadles when folded to inoperative position as shown in Fig. 4.

Means operated in conjunction with the door operating means above described is employed to move the treadles from the folded position shown in Figs. 3 and 4 through the opening in panel 3 to the extended position shown in Fig. 5. As illustrated, this operating means comprises a modified bell crank lever 30 pivotally mounted on a bracket 31 and having an elongated arm 31' rigidly secured to footboard 26. The other arm of said bell crank lever is connected by a link 32 having an adjustable connection 32' therein with one arm of a second bell crank lever 33 pivotally mounted on a suitable bracket beneath the keyboard. The other arm of said second bell crank lever is operatively connected with crank 20 of operating shaft 18 by link 34 having a flattened end portion with an elongated slot 35 therein, in which engages a pin 36 rigidly secured on a projection 37 on said crank (Fig. 6). A spring buffer 38 is secured beneath the keyboard and is arranged to contact with one of the arms of bell crank 33 as the pedals fall by gravity into extended or operative position. This absorbs the shock due to the momentum of the falling parts so that the pedals strike the floor without undue noise.

The operation of the invention, which will be clear from the above description, briefly is as follows:

Assuming that the parts are in folded or

inoperative position as shown in Fig. 1, the operator grasps the handle 19, turning the shaft 18 in a counter-clockwise direction. During approximately the first 90° of rotation of shaft 18, the pin 21 rides in slot 16 of pivoted member 10, rotating the latter to move the door from closed to open position through connections 12, 13, 14 and 15, whereupon pin 21 passes out of the open end of the slot so that there is no further operating connection between shaft 18 and door 5 as the operator continues to rotate the shaft in a counter-clockwise direction. During the greater portion of this movement the pin 36 slides idly in slot 35 so that there may be little or no attendant movement of the treadles. But as the shaft 18 continues to rotate further from the position shown in Fig. 3 toward that shown in Fig. 5, pin 36 engages at the end of slot 35, operating connections 34, 33, 32, and 30 to move the treadles pivotally on bell crank lever 30 through the uncovered opening in panel 3. As the treadles pass beyond their vertical line of support, their pivotal movement may be continued by gravity until the feet 28 engage the floor, the impact of the fall being absorbed by the spring buffer 38 as mentioned above. During this gravity movement of the pedals the pin 36 rides idly through the slot 35 to the opposite end thereof so that the parts are then in proper relative positions to begin the reverse or folding movement of the parts. It will thus be seen that the door and treadles are operated successively to accomplish the desired results. It will be obvious that similar action occurs upon reverse movement of the operating handle to restore the parts to initial position, the parts then being moved in reverse sequential order.

When the panel 3 is removed from the piano for any purpose, pin 21 disengages with slot 16 and the door operating connection is broken, but the treadle operating means is not thereby interfered with. When the panel is replaced the pin and slot again automatically engage so that the parts operate as above set forth.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described, and all statements of the scope of the invention which, as a matter of language, might be said to fall therebetween.

Having described my invention, what I claim as new and desire to secure by Letters Patent, is:—

1. In a player piano, in combination, a case including a removable panel formed with a treadle opening, a movable closure carried by said panel, treadles arranged for movement through said opening between idle position behind the panel and working position in front of the panel, means carried by said casing to move said treadles between said positions, mechanism carried by said panel and operable by said treadle-moving means when the panel is in place to close and uncover said opening subsequently to the movement of said treadles, and means to operatively connect said treadle-moving means with said closure-operating mechanism, said connecting means being arranged to permit the removal of said panel with the closure and the closure-operating mechanism carried thereby while the treadle-operating mechanism remains intact.
2. In a player piano, in combination, a case including a removable panel formed with a treadle opening, a movable closure carried by said panel, treadles arranged for movement through said opening between idle position behind the panel and working position in front of the panel, means carried by said casing to move said treadles between said positions, mechanism carried by said panel and operable by said treadle-moving means when the panel is in place to close and uncover said opening subsequently to the movement of said treadles, and means to operatively connect said treadle-moving means with said closure-operating mechanism, said connecting means comprising a pair of juxtaposed rotatable members mounted respectively on the casing and the panel, said members being arranged to cooperate during the movement of the closure and to be disengaged after one of the movements thereof, said members being adapted to be disconnected by the bodily upward movement of the panel.
3. In a player-piano, in combination, a case including a removable lower front panel having a treadle opening, a sliding closure for said opening carried by said panel, treadles arranged for movement through said opening from idle position behind said panel to working position before said panel and vice versa, means carried by said case and connected to said treadles for moving the latter, and means carried by said panel for moving said closure, said last means including a part having a releasable connection with said first named means released by the removal of the panel.
4. In a player piano, in combination, a case including a removable panel formed with a treadle opening, a movable closure carried by said panel, treadles arranged for movement through said opening between idle position behind the panel and working position in front of the panel, means carried by said casing to move said treadles between said positions, mechanism carried by said panel and operable by said treadle-moving means when the panel is in place to close and uncover said opening subsequently to the movement of said treadles, and means to operatively connect said treadle-moving means with said closure-operating mechanism, said connecting means comprising a pair of juxtaposed rotatable members mounted respectively on the casing and the panel, said members being arranged to cooperate during the movement of the closure and to be disengaged after one of the movements thereof, said members being adapted to be disconnected by the bodily upward movement of the panel.
5. A player piano, including, in combination, a case formed with an opening, a movable panel for covering said opening, a treadle mechanism, means for moving said mechanism through said opening and beyond said case and retracting it within the same, means for moving said panel, including a slotted member, a crank, a projection forming a part of said crank and extendable into the slot of said member whereby upon said crank being moved it will optionally actuate said member or be disconnected therefrom, and means for connecting said crank with said treadle mechanism.

In testimony whereof I affix my signature.

OSCAR H. CARLSON.
